UNITED STATES PATENT OFFICE.

FREDERICK WILLIAM AUSTIN, OF OLDHAM, ENGLAND.

TUBE FRAME FOR HOLDING SPOOLS OF TUFT YARN.

Application filed May 15, 1925, Serial No. 30,644, and in Great Britain May 14, 1924.

This invention of improvements in tube frames for holding spools of tuft yarn for use in looms for weaving tufted pile fabrics and in spools therefor relates firstly to the 5 tube frames which being adapted for receiving and holding spools of tuft yarn are provided with guide tubes for tuft yarn and with engaging parts for engagement with and disengagement from carrying chains 10 for conveying the tube frames and spools of tuft yarn in due order to and from the places at which they are required to be used for the supply of tuft yarn for insertion between warp threads and also provided 15 with parts for enabling them to be engaged and held by mechanism by which the tube frames are removed from the carrying chains and made to insert tuft yarn between warp threads and to cause tuft yarn to be 20 drawn off the spools and are held during the severance of the tufts inserted between warp threads from the yarn on the spools and are afterwards restored to the carrying chains. The invention relates also to the 25 spools for use in tube frames as aforesaid.

This invention consists in part in end plates or brackets for tube frames as aforesaid which tube frames placed in pairs or rows end to end to be operated simultaneously and in alignment for the production 30 of tufted fabrics of any required width by mechanism provided in looms for seizing the tube frames and disengaging them from the carrying chains, and holding and moving them so as thereby to introduce tuft yarns 35 between warp threads and to draw portions of tuft yarn from the spools and to hold such portions taut while the portions inserted between warp threads are severed from 40 the yarn on the spools and afterwards restoring the tube frames to the carrying chains.

The invention consists further in the formation in each of the end plates or brackets for a tube frame of a notch or channel counter-sunk or rabbeted in part or wholly to receive and to afford bearing for a pivot with a flange or head and the provision of a catch or hook on the end plate or bracket for holding a pivot in the notch or channel which 45 ensures that a spool inserted in an end plate or bracket of a tube frame shall be securely held therein against accidental displacement while being easily inserted therein and being easily withdrawn therefrom without the 50 use of tools and provide simple and convenient brakes for preventing spools from

being turned excessively in the tube frames. The invention consists further in pivots with heads or flanges at each end of spools enabling the spools, besides being mounted 60 securely in the end plates or brackets of tube frames, to serve as stays for holding the end plates or brackets against bending or movement on the parts to which they are attached.

The formation of end plates or brackets for tube frames and of spools according to this invention is illustrated in the accompanying drawing in which Fig. 1 is a front elevation and Fig. 2 is a side elevation of a 70 tube frame with end plates or brackets and a spool mounted in it and Fig. 3 is a plan of parts shown in Figs. 1 and 2. Fig. 4 is a perspective view of the inner face of a tube frame end plate seen obliquely from the 75 rear. Fig. 5 is a rear elevation of a tube frame end plate. The same numerals of reference indicate corresponding parts in all the figures.

As shown in the accompanying drawing, 80 an end plate 1 for use in or with a tube frame is formed as to its main body as a flat plate to present a plane surface on the side turned away from the spool 2 mounted in the tube frame. The plate 1 is provided 85 with perforations or holes in the formation of a projection 3 to be provided on it or for lightness or other purposes or for the attachment of parts to the plate 1.

The plate 1 is adapted in the part 4 in its 90 general plane to be inserted between the sideplates of links of a carrying chain and is provided with a projection 5 for engagement with a holder, which projection 5 extends in hook like form in the general direction of the plane of the end plate 1 and at the rear or side turned towards the back of the loom when the tube frame is removed 95 from the carrying chains to supply tuft yarn for insertion between warp threads 100 and is made to point downwardly when the carrying chain supporting the tube frame presents such tube frame to the holder. The projection 5 is made to narrow towards its end so as to fit the correspondingly narrow notch or recess in the holder. Projections 6, 7, extending laterally from the face of the end plate 1 to be turned towards a spool 2 in the tube frame in order to receive attachment of a bar 8 furnished with 105 or formed of yarn tubes 9 are provided to be presented at the rear and bottom when

the end plate 1 being suspended from a carrying chain is in position for disengagement from said carrying chain.

The end plate 1 is provided on the side 5 to be turned towards a spool 2 in the tube frame with ears 3, 10 respectively, with a hole and notch forming bearings for a hook 11 adapted to engage or to hook over a side plate of a link of a carrying chain.

10 The hole and notch in the projections 3, 10 are formed in such position that the part of the hook 11 passing through them lies crosswise of and a little obliquely to the length of the end plate 1 so that the engaging part of the hook 11 for passing over the plate of a chain moves in an arc slightly oblique to the end plate 1.

The hook 11 is provided with a tail or projection 12 hereinafter for simplicity called the tail 12 to receive pressure for disengaging the hook 11 from the plate of a chain. As shown the tail 12 of a hook 11 is made to project from the face of the end plate 1 turned towards a spool 2 mounted in 25 the tube frame. A plate spring 13 secured by a screw 14 to the end plate 1 is made to extend by a bent portion over and to present a projection 15 entering the notch of the ear so as to hold the hook 11 in that notch 30 and to bear by its free end against the back of the hook 11 so as to press the engaging part of the hook 11 over a plate of a chain.

The upper part of the projection 5 serves also to receive contact of part of the device 35 exerting pressure on the tail 12 of the hook 11 and so enables that device to hold the end plate 1 in a holder presented to it. End plate 1 by its outer face adjacent to the projections 6, 7 presents a surface by which a

40 holding part at the side of a loom may cause a tube frame to be gripped in the case of a loom in which one tube frame is used at a time or may cause two or more tube frames to be pressed together endwise in the case of 45 a loom in which two or more tube frames are used in line by means of a curved or a cam like surface provided on a holding part.

The end plate is formed with a notch or channel 16 open at one end and provided 50 with a wall 17 inclined relatively to the general surface of the end plate 1 so that a pivot 18 with a conical head expanding outwardly, in the case shown a wood screw, inserted in the end of a spool 2 may be received within the notch or channel 16 and made to receive bearing in the circular portion of the notch or channel 16 while not protruding from the end plate 1 and being held against withdrawal longitudinally.

60 A resilient hook or catch 19, in the case shown a plate spring, secured on the inner face of the end plate 1 by a pivot 20 riveted in the end plate 1 is formed with a notch 21 which may be made to embrace the shank of 65 the pivot 18 in the end of a spool 2 and

curved so that its free end may project as a handle at one edge of the end plate 1 when the notch 21 embraces a pivot 18 in a spool 2 and at the part 22 near the handle is bent so that it may pass into engagement with a corresponding notch 23 in the end plate 1 so that it may be held thereby against being accidentally turned to release the pivot 18. The catch 19 is made to bear against a spool 2 when the pivot 18 is inserted in the end plate 1 and to act as a brake for controlling the turning of the spool 2 in the tube frame. Fig. 5 shows the catch 19 bowed by its resilience into the form which it presents in the absence of a spool while Fig. 1 shows the catches 19 held in a flattened condition by the ends of a spool inserted in the tube frame.

Two end plates 1 of the formation hereinbefore described but of opposite hand in the formation and disposition of the parts formed on or applied to them are provided for use at the opposite ends of a tube frame.

End plates provided according to this invention enable tube frames to be applied close together end to end in lines of any length which it may be requisite to use in a loom of any width and are also easily held with security and precision in the parts by which they are moved from carrying chains and moved in the places or place of use in a loom and moved back to carrying chains.

Variations may be made in the formation of end plates for tube frames according to this invention. For example the hooks for engaging carrying chains may be differently mounted in or on the end plates, as for example by being mounted each in two holes or in two notches instead of in one hole and one notch or may be made to turn about axes or to present their tails in positions more or less different from those indicated in the drawing provided that the arms for engaging with the tails of the hook are made to work in suitably corresponding positions or directions. As a further example of a modification in the formation of an end plate the notch may be formed with a ledge around its wall and the pivot of a spool for insertion in it may be formed with a flange or collar to engage with that ledge while not protruding from the end plate. Again the catch provided on an end plate may be contrived or furnished with a part to enter or to fill the part of the notch not occupied by a pivot therein or other means for holding the catch in engagement with a pivot may be provided.

What I do hereby claim as my invention and desire to secure by Letters Patent is:—

1. In a tube frame of the character described, end plates each characterized by being formed mainly as a plate of metal which presents a plane outer surface directed outwardly away from a spool in the tube

- frame and presents in its general plane a part for insertion between the side plates of a link of a carrying chain and also presents in its general plane and at the rear edge thereof, a hook-like projection for engagement with a holder for moving it to and from and holding it while away from a carrying chain.
2. In a tube frame of the character described, end plates each characterized by being formed mainly as a plate of metal which presents a plane outer surface directed outwardly away from a spool in the tube frame and presents in its general plane a part for insertion between the side plates of a link of a carrying chain and also presents in its general plane and at the rear edge thereof, a hook-like projection for engagement with a holder for moving it to and from and holding it while away from a carrying chain, and ears on the side turned towards a spool mounted in the tube frame, one of said ears having a hole and the other a notch, a hook mounted in said ears for hooking over a side plate of a carrying chain, and a spring secured to the end plate for pressing on the hook to hold it in engagement with a link of a carrying chain and having a part extending over said notch to hold the hook therein.
3. In a tube frame of the character described, end plates each characterized by being formed mainly as a plate of metal which presents a plane outer surface directed outwardly away from a spool in the tube frame and presents in its general plane a part for insertion between the side plates of a link of a carrying chain and also presents in its general plane and at the edge thereof which is at the rear and bottom when in position for removal from a carrying chain, a hook-like projection for engagement with a holder for moving it to and from and holding it while away from a carrying chain, presenting a channel wider at the outer surface of the end plate than on the inner surface thereon to afford bearing for a headed pivot of a spool and to receive the whole of the head of said pivot.
4. In a tube frame of the character described, end plates each characterized by being formed mainly as a plate of metal which presents a plane outer surface directed outwardly away from a spool in the tube frame and presents in its general plane a part for insertion between the side plates of a link of a carrying chain and also presents in its general plane and at the edge thereof which is at the rear and bottom when in position for removal from a carrying chain, a hook-like projection for engagement with a holder for moving it to and from and holding it while away from a carrying chain, presenting a channel wider at the outer surface of the end plate than on the inner surface
- thereon to afford bearing for a headed pivot of a spool and to receive the whole of the head of said pivot and further presenting a notch to receive engagement of a resilient catch, and a resilient catch pivoted on the end plate to hook over a pivot in said channel and to engage with said notch.
5. In a tube frame of the character described, end plates each characterized by being formed mainly as a plate of metal which presents a plane outer surface directed outwardly away from a spool in the tube frame and presents in its general plane a part for insertion between the side plates of a link of a carrying chain and also presents in its general plane and at the edge thereof which is at the rear and bottom when in position for removal from a carrying chain, presenting a channel wider at the outer surface of the end plate than on the inner surface thereon to afford bearing for a headed pivot of a spool and to receive the whole of the head of said pivot and further presenting a notch to receive engagement of a resilient catch, and a catch laterally resilient to tend to spring inwardly of the tube frame and pivoted on the end plate to hook over a pivot in said channel and to engage with said notch.
6. In a tube frame of the character described, an end plate presenting a plane surface directed outwardly away from a spool in the tube frame, a part for insertion between the side plates of a link of a carrying chain, an engaging part extending for engagement with a holder for moving it to and from a carrying chain and holding it while away therefrom and ears on the side of the end plate to be turned towards a spool mounted in the end plate, one such ear having a notch, a hook mounted in said ears and adapted to engage a side plate of a link of a carrying chain and presenting a tail to be engaged by disengaging and holding means on a holder to be presented to and made to hold that end plate, a spring secured on said end plate to press on the hook to hold it in engagement with a carrying chain and extending over said notch to hold the hook therein.
7. In a tube frame of the character described, an end plate presenting a plane surface directed outwardly away from a spool in the tube frame, a part for insertion between the side plates of a link of a carrying chain, an engaging part extending for engagement with a holder for moving it to and from a carrying chain and holding it while away therefrom and a channel with non-parallel walls to receive and to afford bearing for the head of a headed pivot on a spool so that the pivot shall not protrude through the end plate and, in combination with said end plate, a spool with a headed pivot for engagement in said channel.

8. In a tube frame of the character described, an end plate presenting a plane surface directed outwardly away from a spool in the tube frame, a part for insertion between the side plates of a link of a carrying chain, an engaging part extending for engagement with a holder for moving it to and from a carrying chain and holding it while away therefrom and a channel with 10 non-parallel walls to receive and to afford bearing for the head of a headed pivot on a spool so that the pivot shall not protrude through the end plate and a notch to receive engagement of a catch, a hook mounted in said ears and adapted to engage a side plate of a link of a carrying chain and presenting a tail which projects from the end plate on the side to be 15 turned towards a spool mounted in the tube frame and is adapted to be engaged by disengaging and holding means on a holder to be presented to and to be made to hold that end plate, a spring secured on said end plate 20 to press on the hook to hold it in engagement with a carrying chain and extending over said notch in said ear to hold the hook therein and a resilient catch pivoted to said end plate to engage with a pivot of a spool 25 in said channel to hold it therein and to bear against said spool and to engage the notch provided for engagement of it in the end plate and, in combination with said end plate, a spool with a headed pivot for 30 engagement in said channel and to receive contact of said catch.

9. In a tube frame of the character described, an end plate presenting a plane surface directed outwardly away from a spool in the tube frame, a part for insertion between the side plates of a carrying chain, a hook-like engaging part extending in the 25 general plane of the plate for engagement with a holder for moving it to and from a carrying chain and holding it while away therefrom, projections at the parts to be at the bottom and rear when the end plate is in position for disengagement from a carrying chain extending laterally from the face to be turned towards a spool in the tube frame and providing attachment for a bar pro-

vided with yarn tubes, ears on the side of the end plate to be turned towards a spool 35 mounted in the end plate, one such ear having a notch and a channel with non-parallel walls to receive and to afford bearing for the head of a headed pivot on a spool so that the pivot shall not protrude through the end plate and a notch to receive engagement of a catch, a hook mounted in said ears and adapted to engage a side plate of a link of a carrying chain and presenting a tail which projects from the end plate on the side to be 40 turned towards a spool mounted in the tube frame and is adapted to be engaged by disengaging and holding means on a holder to be presented to and to be made to hold that end plate, a spring secured on said end plate 45 to press on the hook to hold it in engagement with a carrying chain and extending over said notch in said ear to hold the hook therein and a resilient catch pivoted to said end plate to engage with a pivot of a spool 50 in said channel to hold it therein and to bear against said spool and to engage the notch provided for engagement of it in the end plate and, in combination with said end plate, a spool with a headed pivot for 55 engagement in said channel and to receive contact of said catch.

In testimony that I claim the foregoing as my invention, I have signed my name this fifth day of May 1925.

FREDERICK WILLIAM AUSTIN.

CERTIFICATE OF CORRECTION.

Patent No. 1,664,015.

Granted March 27, 1928, to

FREDERICK WILLIAM AUSTIN.

It is hereby certified that error appears in the above numbered patent requiring correction as follows: In the heading to the printed specification line 5, date of filing application in Great Britain, for May 14, 1924 read May 17, 1924; and that the said Letters Patent should be read with this correction therein that the same may conform to the record of the case in the Patent Office.

Signed and sealed this 15th day of May, A. D. 1928.

(Seal)

M. J. Moore,
Acting Commissioner of Patents.
